UNITED STATES PATENT OFFICE.

JOSEPH B. SARGENT, OF NEW HAVEN, CONNECTICUT.

DESIGN FOR A FUNERAL ORNAMENT.

SPECIFICATION forming part of Design No. 12,032, dated November 9, 1880.

Application filed September 13, 1880. Term of patent 14 years.

To all whom it may concern:

Be it known that I, JOSEPH B. SARGENT, of New Haven, in the county of New Haven and State of Connecticut, have invented a new 5 Funeral Ornament; and I do hereby declare the following, when taken in connection with the accompanying drawing and the letters of reference marked thereon, to be a full, clear, and exact description of the same, and which 10 said drawing constitutes part of this specification, and represents a perspective view.

This invention relates to a design for emblematical ornaments for funeral purposes— 15 as, for instance, coffin-trimmings or mingled with flowers; and it consists of an open chrysalis on a leaf, as hereinafter described, and shown in the accompanying illustration.

On a base, A, in the form of a leaf, is the representation of an open or deserted chrysalis, C.

The kind of leaf may be varied without departing from the design, the essential feature being the representation of an open chrysalis as attached to a leaf or similar base.

I claim—

The design for funeral ornaments, consisting of the representation of an open chrysalis on a base, as herein described, and shown in the accompanying illustration.

JOSEPH B. SARGENT.
